ALEXANDER M. PASNIK, OF NORWICH, CONNECTICUT.

SUGAR BOWL.

Application filed June 16, 1926. Serial No. 116,253.

The invention relates to table articles such as sugar bowls, and has for its object to provide a dispensing receptacle of advantageous nature adapted to be adjusted 5 either for continuous discharge or for charge dispensing, and whereby also the rate of discharge can be regulated.

The vessel has a container chamber and a small charge chamber communicating by a 10 throat, with connected valves on an operating rod, and a screw adjustment the setting of which determines whether the upper valve will close the throat or leave it open when the lower valve is unseated from the 15 outlet of the charge chamber. With the former condition only the contents of the charge chamber are delivered at each depression of the operating part, while in the latter condition material will pass from the 20 large chamber to the open outlet by way of the charge chamber as long as the part is held depressed. The adjustment enables the degree of opening of the outlet for continuous discharge to be varied, for slower 25 or more rapid flow, the extent of opening that will be produced increasing as the setting of the adjustment approaches the charge dispensing condition.

In the accompanying drawings forming 30 part hereof:

Fig. 1 is a vertical sectional view with part in elevation of a sugar bowl embodying the invention, showing the outlet closed and the upper valve above the throat, the 35 parts being adjusted for the dispensing of single charges;

Fig. 2 is a similar view showing the movable part depressed as far as it will go, unseating the lower valve and causing the 40 upper valve to close the throat; and

Fig. 3 is a similar view showing an adjustment for continuous discharge, full lines showing the normal position, and dotted lines showing the movable part as if depressed.

The bowl 2 is supported by a foot 3 and pedestal 4. The bowl encloses the main chamber or container 5, having a circular opening 6 in its bottom, with the bottom 50 sloping from all sides to the opening. A shell 7 fixed inside the hollow pedestal forms a small charge chamber 8, having a curved bottom containing an outlet opening 9.

55 The top of the bowl 2 has a wide mouthed

rim 10, with a spider fixed therein supporting a central spring barrel 11, which is open at the top and has an abutment 12 at the bottom. A centrally apertured cover 13 fits within the rim 10 and about the spring 60 barrel 11.

A rod 14 stands vertically in the bowl, and has a valve member 15 formed on its lower end, which is adapted to seat upwardly against the edge of the outlet 9, to close 65 the same. An upper valve member in the form of a cylindrical enlargement 16 is formed on the stem at such distance above the lower valve that, when the lower valve is closed against the outlet, the upper valve 70 is raised above the opening 6, leaving this throat between the two chambers open.

The upper end of the rod 14 is screw-threaded for a considerable portion of its length, marked 17, and an operating button 75 18 is provided with a fairly long screw-threaded socket 19 which receives the screw-threaded portion of the stem. This screw is designed to permit the button to be screwed up or down on the rod within a range 80 of adjustment which will be apparent from a comparison of Figs. 1 and 3.

The button 18 has a shoulder 20 which is opposed to cooperating stop means on the bowl afforded by the upper end 21 of the 85 spring barrel. This stop limits the extent to which the button may be depressed.

A spring 22, preferably attached to the button 18 and bearing against the bottom 12 of the spring barrel, constantly urges the 90 rod, button and valves upward, normally holding the lower valve against the outlet.

The relations, including the spacing between the two valves and the range of adjustment, are such that, with the adjustment 95 shown in Figs. 1 and 2, the upper valve will be moved down to or into the throat 6, closing the communication between the chambers, when the button is pushed down as far as it will go, moving the lower valve 100 away from the outlet. Consequently, in this condition, only the contents of the charge chamber 8 will be delivered, and to obtain another charge it is necessary to let the movable part rise, so as to close the outlet 105 and open the throat, in order that the charge chamber may be refilled from the main chamber, before again pushing down on the button. On the other hand, if the button is screwed down on the stem, as shown in 110

Fig. 3, the depression resulting when the button is pushed down to the stop will not be sufficient to cause the upper valve 16 to close the throat 6, this valve being still above the throat, as shown in dotted lines. Therefore, not only the contents of the charge chamber will be delivered past the unseated lower valve 15, but the granular material will continue to pass from the main chamber to the subchamber and thence through the outlet, as long as the button is held down.

In the adjustment illustrated in Fig. 3, the extent to which the outlet valve can be opened by depression is quite small, so that a comparatively slow continuous discharge is permitted. The spacing of the valves is such, however, that there is a range of adjustment before the charge dispensing condition of Figs. 1 and 2 is reached, within which range greater degrees of opening of the outlet valve for more rapid continuous discharge can be obtained.

While the preferred form of the invention has been described in detail, it will be understood that there may be numerous changes in the specific construction and arrangement without departing from essen-

tials. I do not limit myself to the precise form and arrangement of the adjustment.

What I claim as new is:

A dispensing table article comprising a container chamber, a charge chamber beneath the container chamber, there being a throat at the bottom of the container chamber opening into the charge chamber, and the charge chamber having a bottom outlet, a part having a lower valve normally seated upward against said outlet and an upper valve normally occupying a position above said throat, a spring pressing said part upward, a stop distinct from said throat for limiting the depression of said part, and a means of screw adjustment between said part and stop, the range of adjustment of said means being such that the depression produced when the part is pushed down to the limit of said stop can be so regulated that either the upper valve fails to close the throat with the lower valve unseated, resulting in continuous discharge, or the upper valve closes the throat when the lower valve is unseated, in which event a charge only is dispensed.
